A mining machine is provided with a lock for the starting device, the lock being withdrawn by a piston and cylinder operated by a bleed from the dust suppression fluid supply, and a restriction is provided in the bleed for causing a delay in the withdrawal of the lock from the moment when the dust suppression fluid is turned on, whereby the machine cannot be started before the dust suppression fluid has been supplied to the cutting head for a period sufficient to warn away any personnel working on or in the region of the cutting head.

STARTING CONTROL LOCK BY DUST SUPPRESSION CONTROL IN MINING MACHINE

This invention relates to mining machines and has for its object the provision of means for ensuring that personnel have been warned away from the cutting heads before the machines are started.

According to the present invention, a mining machine comprises a starting device, dust suppression equipment for emitting fluid in the region of the cutting head, a manually operated valve for stopping the dust suppression fluid, a lock urged by a spring towards a position in which it prevents operation of the starting device, a piston and cylinder for effecting withdrawal of the lock against the urge of the spring, a bleed from the dust suppression fluid supply between the valve and the cutting head for providing pressure in the cylinder at the side of the piston for effecting withdrawal of the lock, and a restriction in the bleed for causing a delay in the withdrawal of the lock from the moment the dust suppression fluid valve is opened. The dust suppression fluid may be water or foam, or any other suitable liquid.

Thus, the lock constitutes an interlock between the dust suppression equipment and the starting device, whereby the machine cannot be started before the dust suppression fluid is being supplied to the cutting head, and the delay in the withdrawal of the lock caused by the restriction in the bleed from the fluid supply results in a delay in the starting of the machine until fluid has been emitted in the region of the cutting head for a period sufficient to warn away any personnel working on or in the region of the cutting head.

The lock may take various forms depending upon the nature of the starting device of the mining machine.

Thus, if the starting device comprises a handle movable manually between "off" and "on" positions, the lock may comprise the free end of the piston rod, which engages a projection, e.g., a step or shoulder or outwardly spring-loaded pawl on a cam, on a shaft rotatable by the starting handle. If the starting handle is movable from an "off" position in either direction, to "forward" and "reverse" positions respectively, i.e., the machine is adapted to cut in both directions of travel, then two mutually-facing projections (steps, shoulders, or outwardly spring-loaded pawls) are provided to ensure that the handle cannot be moved in either direction before the dust suppression fluid is being supplied to the cutting head.

On the other hand, if the starting device comprises a push-button switch, the lock may comprise a guard on the free end of the piston rod and preventing access to the push-button before the dust suppression fluid is being supplied to the cutting head. Alternatively, the lock may comprise the free end of the piston rod, which upon withdrawal actuates a cut-out switch in series with the push-button switch, so that the push-button switch cannot become effective before the dust suppression fluid is being supplied to the cutting head.

The restriction in the bleed is preferably adjustable, e.g., it may consist of a needle valve with screw adjustment of the needle, so that the delay (and, consequently the duration of the period of fluid emission before the starting handle can be turned) can be adjusted to suit the particular machine or working conditions to give the personnel reasonable time to get clear of the cutting head.

The restriction is preferably provided in a by-pass round a non-return valve lightly spring-loaded to closed position in the direction of flow of fluid in the bleed for effecting withdrawal of the lock, so that upon closing of the valve to stop the supply of fluid to the cutting head, the spring return of the lock towards locking position operates with the minimum of delay.

The bleed from the fluid supply preferably effects withdrawal of the lock through a fluid pressure transmission device in which the dust suppression fluid is separated by a "fluid transfer barrier" (e.g., a diaphragm, bellows, bag, or piston) from hydraulic fluid for the lock cylinder, so that particles in the dust suppression fluid cannot reach and cause damage to the piston or cylinder. However, it is preferable to provide a filter for the hydraulic fluid. The side of the piston not subjected to hydraulic fluid pressure is preferably bled to an atmospheric space enclosed within a bellows, or to atmosphere through a filter, so that — likewise — particles in the environment cannot reach and cause damage to the piston or cylinder.

The machine is preferably also provided with an audible warning device, which likewise may be operated by a bleed from the dust suppression fluid supply, e.g., to another fluid pressure transmission device in which the dust suppression water is separated from air for blowing the audible warning device by a diaphragm, bellows, bag, or piston, i.e., the fluid pressure transmission device acts as a "fluid operated pump."

One embodiment of the invention and a couple of modifications will now be described, by way of example only, with reference to the accompanying drawings, in which :

FIG. 1 is a diagram showing the dust suppression and safety equipment for a mining machine according to the invention;

FIG. 2 is a section of the delay device of FIG. 1, to a larger scale and taken from the line II—II of FIG. 3;

FIG. 3 is a section from the line III—III of FIG. 2;

FIG. 4 is an enlarged section of the lock device of FIG. 1, taken on the line IV—IV; and

FIGS. 5 to 7 correspond to the upper part of FIG. 4 but shows three modifications.

In FIG. 1, a supply 1 of water for a mining machine passes through a branch connector 2 for a hose 3 leading to a fire fighting nozzle 4 incorporating its own valve, before reaching a shut-off valve 5 connected to a strainer 6 at which the flow is divided. One outlet 7 of the strainer is connected by a hose 8 to the cooling water passages of a motor 9 for driving the mining machine and from there hoses 10 convey the cooling water to a bank of fixed sprays 11 for effecting dust suppression when the machine is in operation. Another outlet 12 of the strainer is connected by a hose 13 to a manifold 14, one outlet from which is connected by a hose 15 to an adjustable spray 16 with a guard 17, the spray 16 being set to provide the main flow of dust suppression water, directed (by adjusting the attitude of the spray 16) where required.

The outlet 7 of the strainer 6 also has a bleed passing through a branch connector 18 with a relief valve 19 controlling the pressure of the bleed water in a hose 20 connected to one end of a fluid pressure transmission device 21 having a bag 22 (or "fluid transfer barrier") separating the water from hydraulic fluid (which it pressurises), the other end of the fluid pressure transmission device being connected by a hose 23 to a delay

device 24, the outlet of which is connected by a hose 25 to a lock device 26 controlling the starting of the mining machine motor 9 in a manner to be described presently.

Another outlet from the manifold 14 is connected by a hose 27 to another fluid pressure transmission device 28 in which the dust suppression water is separated by a piston (or "fluid operated pump") from air (which it pressurises) for blowing an audible warning device 29 connected to the fluid operated pump by a hose 30.

In FIGS. 2 and 3 hydraulic fluid entering the delay device 24 through a connector 31 for the hose 23 from the fluid pressure transmission device 21 is prevented from passing into a bore 32 leading to a connector 33 for the hose 25 to the lock device 26 by a spring-loaded non-return valve 34 in a chamber 35, but the fluid can pass through a lateral passage 36 into a chamber 37 having a filter 38 through which the fluid must pass in order to reach a reducing valve 39 which sets the pressure of the fluid communicated to a needle valve 40 (FIG. 3) providing a restriction for delaying the flow to another lateral passage 41 leading to the bore 32, bypassing the valve 34. The needle valve has a screw-adjustable plug carrying the needle 42 enabling the duration of the delay to be preset. The delay device 24 is primed by forcing hydraulic fluid into the chamber 37 through a check valve 43 and a filter 44.

In FIG. 4 hydraulic fluid enters the lock device 26 through a connector 45 (see also FIG. 1) for the hose 25 from the delay device 24 and acts on a piston 46 in a cylinder 47, against the urge of a spring 48, to effect withdrawal of a lock 49 comprises by the free end of the piston rod 50 from engagement with an outwardly spring-loaded pawl 51 on a cam 52 on a shaft 53 rotated by the starting handle (not shown) of the mining machine. The cam 52 and shaft 53 are shown in the "off" position, and the direction of rotation to the "on" position is anti-clockwise, so that until the lock 49 is withdrawn the shaft 53 cannot be rotated to the "on" position. The lock cannot be withdrawn until a sufficient pressure has built up in the cylinder 47 to move the piston 46 against the urge of the spring 48, and because of the restriction set by the restrictor 40 this pressure will not build up for some little time after the dust suppression water sprays 11 and 16 have come into action, so the machine cannot be started until after the sprays have been in action for some time to serve as a warning.

There being no restriction in the supply of water to the fluid pressure transmission device 28, the audible warning device 29 will be operated as the sprays 11 and 16 start, thus warning any personnel not noticing the water sprays that the machine is liable to be started at any moment.

Seven seconds has been found to be ample warning to anyone working near the cutting head of the machine that it is about the start. However, starting of the machine is a separate manual operation (i.e., rotation of the shaft 53 once the lock 49 has been withdrawn clear of the pawl 51 on the cam 52) so it is still possible for the operator of the machine to make additional checks, even though such checks should not be necessary.

When the machine has been stopped (by rotating the shaft 53 clockwise) the dust suppression water can be stopped by means of the shut-off valve 5, and the fluid exhausted back from the lock device 26 (allowing the

spring 48 to urge the piston 46, rod 50 and lock 49 back to the position shown in FIG. 4) opens the valve 34, thus communicating directly from the bore 32 to the chamber 35 and thence to the fluid pressure transmission device 21, as the pressure fades at the sprays 11 and in the hoses 8, 10. Should the water be turned off before the machine is stopped, so that the lock 49 returns to locking position before the shaft 53 is returned to the "off" position, rotation of the shaft will not be obstructed because the pawl 51 will depress to pass the lock and then spring out again to the position shown in FIG. 4.

The side of the piston 46 not subjected to fluid pressure (i.e., the side with the spring 48) is bled to atmosphere through a filter 54, so that particles in the environment cannot reach and cause damage to the piston 46 and cylinder 47, just as they are likewise protected by the bag 22 of the fluid pressure transmission device 21 from particles in the dust suppression water.

In FIG. 5 the cam 52 is provided with two mutually-facing outwardly spring-loaded pawls 51A, 51B for use with a starting handle (not shown) movable in one direction from an "off" position (as shown) to a "forward" position or in the opposite direction to a "reverse" position, i.e., if the machine is adapted to cut in both directions of travel.

In FIG. 6, a guard 55 on the free end 49 of the piston rod prevents access to a push-button start switch 56 until the dust suppression water is being supplied to the cutting head of the machine, but a stop button 57 remains accessible at all times.

In FIG. 7, the free end 49 of the piston rod acts through a spring-loaded push rod 58 to hold the contacts (not visible) of a switch 59 open until the dust suppression water is being supplied to the cutting head of the machine, the switch 59 being in series with a push-button switch (e.g., such as the switch 56 without any guard) for starting the machine, which latter switch cannot, therefore, be actuated until the contacts of the switch 59 have been closed.

What we claim is:

1. A mining machine comprising a starting device, dust suppression equipment for emitting fluid in the region of the cutting head, a manually operated valve for stopping the dust suppression fluid, a lock urged by a spring towards a position in which it prevents operation of the starting device, a piston and cylinder for effecting withdrawal of the lock against the urge of the spring, a bleed from the dust suppression fluid supply between the valve and the cutting head for providing pressure in the cylinder at the side of the piston for effecting withdrawal of the lock, and a restriction in the bleed for causing a delay in the withdrawal of the lock from the moment the dust suppression fluid valve is opened.

2. A mining machine as in claim 1, wherein the starting device comprises a handle movable manually between "off" and "on" positions, and the lock comprises the free end of the piston rod, which engages a projection on a shaft rotatable by the starting handle.

3. A mining machine as in claim 2, wherein the projection is an outwardly spring-loaded pawl on a cam on the shaft rotatable by the starting handle.

4. A mining machine as in claim 1, wherein the starting device comprises a starting handle movable from an "off" position in either direction, to "forward" and "reverse" positions respectively, and the lock com-

prises the free end of the piston rod, which engages the mutually-facing projections on a shaft rotatable by the starting handle.

5. A mining machine as in claim 4, wherein each projection is an outwardly spring-loaded pawl on a cam on the shaft rotatable by the starting handle.

6. A mining machine as in claim 1, wherein the starting device comprises a push-button switch, and the lock comprises a guard on the free end of the piston rod and preventing access to the push-button before the dust suppression fluid is being supplied to the cutting head.

7. A mining machine as in claim 1, wherein the starting device comprises a push-button switch, and the lock comprises the free end of the piston rod, which upon withdrawal actuates a cut-out switch in series with the push-button switch, so that the push-button switch cannot become effective before the dust suppression fluid is being supplied to the cutting head.

8. A mining machine as in claim 1, wherein the restriction is adjustable.

9. A mining machine as in claim 8, wherein the restriction consists of a needle valve with screw adjustment of the needle.

10. A mining machine as in claim 1, wherein the restriction is provided in a by-pass round a non-return valve lightly spring-loaded to closed position in the direction of flow of fluid in the bleed for effecting withdrawal of the lock.

11. A mining machine as in claim 1, wherein the bleed from the dust suppression fluid effects withdrawal of the lock through a fluid pressure transmission device in which the dust suppression fluid is separated by a "fluid transfer barrier" from hydraulic fluid for the lock cylinder.

12. A mining machine as in claim 11, wherein the side of the piston not subjected to fluid pressure is bled to atmosphere through a filter.

13. A mining machine as in claim 1 provided with an audible warning device.

14. A mining machine as in claim 13, wherein the audible warning device is operated by a bleed from the dust suppression fluid supply.

15. A mining machine as in claim 14, wherein the bleed for the audible warning device effects operation of the warning device by another fluid pressure transmission device.
